UNITED STATES PATENT OFFICE.

ALFRED ERNEST TERRY, OF REDDITCH, ENGLAND.

EXERCISING APPARATUS.

SPECIFICATION forming part of Letters Patent No. 743,204, dated November 3, 1903.

Application filed January 14, 1901. Serial No. 43,278. (No model.)

To all whom it may concern:

Be it known that I, ALFRED ERNEST TERRY, of the firm of Herbert Terry & Sons, of Novelty Works, Redditch, in the county of Worcester, England, have invented certain new and useful Improvements in Exercising Apparatus; and I hereby declare that the following is a full, clear, and exact description of the same.

My invention has for its object improvements in chest-expanders, exercisers, and the like by which I increase the life of such articles and at the same time considerably improve their appearance with a reduction in the cost of manufacture. Hitherto the elastic portion of this class of expander or exerciser has been formed of india-rubber, which in the course of time loses its nature and elasticity and becomes hard and brittle, especially if subjected to extreme changes of temperature, to obviate which I form the extensible portion of such exercisers of metallic spring-coils, as hereinafter described.

In the accompanying drawings, Figure 1 is an elevation of a single chest-expander. Fig. 2 is a longitudinal section through same.

In carrying this invention into effect the metallic spring-coils A are formed by coiling steel or other suitable wire of various gages and section into springs, which may be varied in section as desired, but which I prefer to form of circular section, as shown. The ends of these metallic spring-coils are bent round to form rings B, to which the handles C are linked in such a manner as to allow of the most perfect lateral flexibility between the handles C and metallic spring-coils A. In cases where it is desired to restrict the extensibility of the metallic spring-coils within certain limits the spring-tape, cord, or metallic connection D of limited extensibility is provided to connect the two ends B of the metallic coils A together, such connection passing through the interior of the said metallic coil, which thus forms a covering to the connecting medium D. In case of using a thin-wire connection D the wire is crimped or coiled to easy curves over its whole length for the better assembling of the wire when the metallic coil returns to its normal-state disposition.

The strength of the metallic expanders and exercisers can be varied by the use of differ-

ent gages of wire in the manufacture of the coils, or one or more metallic coils may be contained one within the other and such internal coils may be made detachable, and thus enable the user to adjust the power of the exerciser to suit varying requirements. 55

In the case of steel wire the coils are nickel-plated or may be otherwise covered to further improve their appearance. 60

The means for connecting the handles to the metallic coils both interchangeably and otherwise may be varied so long as flexibility is maintained in the joint or connection between the two and further that in the case of the interchangeable expanders and exercisers such connections shall be so securely fastened that there is no possibility of their becoming accidentally disconnected. 70

Having now particularly described and ascertained the nature of my said invention and in what manner the same is to be performed, I declare that what I claim is—

1. In an exercising apparatus, the combination of an exterior spring-coil, a metallic spring-coil of limited extensibility surrounded by said exterior coil, and means for operating the coils connected with the ends of the exterior coil. 75

2. In an exercising apparatus, the combination of an outer spring-coil, a metallic spring-coil of limited extensibility surrounded by the outer coil, and means formed upon the extremities of the outer coil for connecting 85 the inner coil to the outer coil.

3. In an exercising apparatus, the combination of an outer metallic spring-coil, a handle flexibly connected to each end thereof, and a metallic spring-coil surrounded by said 90 coil and having its ends connected to the ends of the outer coil.

4. In an exercising apparatus, the combination of an outer metallic spring-coil, a handle flexibly connected to each end thereof, 95 and a metallic spring-coil of limited extensibility surrounded by the outer coil and connected to said coils' ends for restricting the undue extension of the outer coil.

5. In an exercising apparatus, the combination of an outer metallic spring-coil having its ends extending across the end coils thereof, a handle connected to said ends of the coil, and a metallic spring-coil within the outer 100

spring-coil of a different tension having its ends connected to the ends of the outer coil, for the purpose set forth.

6. In an exercising apparatus, the combination of an outer metallic coil, rings formed by the ends of said coil, a metallic spring-coil of limited extensibility having its ends connected to said rings and incased by the outer

coil, and means for extending the coils connected to the rings.

In witness whereof I have hereunto set my hand in the presence of two witnesses.

ALFRED ERNEST TERRY.
